UNITED STATES PATENT OFFICE.

OLIVER B. WOODROW, OF NEWTON, IOWA.

WASHING-MACHINE CLUTCH MECHANISM.

Application filed September 27, 1921. Serial No. 503,642.

To all whom it may concern:

Be it known that I, OLIVER B. WOODROW, a citizen of the United States, and resident of Newton, in the county of Jasper and State of Iowa, have invented a certain new and useful Washing-Machine Clutch Mechanism, of which the following is a specification.

This invention relates to improvements in electric washing machines, and particularly to improvements in clutch devices in the class of washing machines such as illustrated and described in my Patent Number 1,275,515, issued August 13, 1918.

In this patent, the clutch member 40 is splined to a shaft 31, which shaft is driven by means of suitable gearing devices, a part of which is replaced in my present application by a belt. The clutch 40 is designed to operate a crank wheel 34 which is loosely mounted on a shaft, the said crank wheel being designed to actuate the agitator shaft 15 through the links 20 and 35 and the rocker arm 19.

I have found by actual practice that a large amount of play is developed between the clutch 40 and the spline to which it is operatively mounted on the shaft 31, and also some play develops between the clutch members 40 and 41 after the machine has been operated for some time. In fact it is almost impossible to machine the parts so they will fit without play and at the same time be easy to operate to throw the machine into and out of gear. When play between the clutch 40 and the shaft 31 has developed, a sort of intermittent movement of the crank wheel 34 will be produced, and also a pounding noise as the said crank passes its dead centers.

It is, therefore, the object of my invention to provide in connection with a washing machine employing a crank member with means for throwing the said crank into and out of gear with a continuously operating shaft, an improved clutch device for connecting the continuously operating shaft and the crank member in such a manner that as the two members are in operative relation with each other, all play and noise will be eliminated.

A further object is to provide in a washing machine having an electric motor and a mechanism for actuating a washing member, improved means for throwing the washing

members into and out of operative relation with the said electric motor.

A still further object is to provide a clutch device for throwing washing machines into and out of gear of simple, durable and inexpensive construction.

These and other objects will be apparent to those skilled in the art.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a side elevation of a washing machine embodying my invention.

Figure 2 is a horizontal sectional view taken on the line 2—2 of Figure 1.

Figure 3 is a detail sectional view taken on the line 3—3 of Figure 2.

Figure 4 is a detail side elevation of one of the clutch members of my improved device.

The numeral 10 indicates generally a frame of a washing machine upon which is pivotally mounted a tub 11.

Mounted in the tub 11 is an agitator shaft 12 upon which is mounted a pinion gear 13 which is operatively connected with a rack 14.

The free end of the rack bar 14 is pivotally mounted to the upper end of a rocker arm 15 having its central portion 16 pivoted to a bracket member 17, this bracket being secured to one side of the tub 11.

The lower end of the rocker arm 15 is provided with a pivoted link 18 which is for the purpose of imparting an oscillating movement to the bar 15 and motion to the agitator shaft 12, this mechanism being similar to that disclosed in my previous patent as above mentioned.

For operating the link 18, I have provided the following mechanism:

Rotatively mounted within the frame 10, I have provided a shaft 19 provided at one end with a beveled gear 20 which is in mesh with a beveled gear 21 secured to the lower end of a vertically arranged shaft 22. This shaft 22 is for the purpose of driving the wringer mechanism not shown.

One end of the shaft 19 is mounted in a bearing member 23, while the opposite end is mounted in a hub 24 of a gear 25. This

hub 24 is rotatively mounted in a bearing 26 carried by a bracket 27. This bracket 27 and the bearing member 23 are supported in the frame 10. The gear 25 is rigidly secured to the shaft 19 by means of a pin 28.

Rotatively mounted in the supporting brackets of the bearings 26 and 23 in front of the shaft 19, I have provided a shaft 30 provided with a pinion 31 and designed to mesh with the teeth of the gear 25.

The inner end of the shaft 30 is provided with a belt wheel 32 driven by means of a motor 33 through a belt 34. The belt 34 is provided with an idler pulley 35 mounted on a pivotally mounted arm 36 and so arranged that the weight of the pulley 35, and the said arm 36, will always hold the belt tight and automatically take up any stretch of the belt 34.

Rotatively and slidably mounted on the inner end of the shaft 19, I have provided a disc 37 having a hub 38 and a rim portion 39.

The outer face of the disc 37 is provided with a crank pin 40 operatively connected with the link 18. The inner face of the disc 37 is provided with two semi-annular flanges 41, each of the said flanges being provided with an enlarged clutch portion 42. The adjacent faces of the members 42 are radial and also slightly tapered, as clearly shown in Figure 2.

The gear 25 is provided with lugs 43 which have tapering faces which are designed to coat with the tapering faces of the members 42 when the disc 37 is in one of its positions upon the shaft 19.

For moving the disc 37, I have provided a yoke member 44 having each end provided with inwardly extending flanges 45 designed to receive the rim 39 of the disc 37 between them.

The member 44 is provided with an arm 46 which is rigidly secured to a shaft 47. The inner end of the shaft 47, as clearly shown in Figure 3, is provided with a spring 48 and a washer 49, the washer being secured in position by means of a key 50.

The spring 48 is so arranged that the shaft 47 will be moved longitudinally and inwardly, and will cause the members 42 of the flanges 41 to engage the tapering blocks 43 of the gear 25.

Pivotedly mounted on the outer end of the shaft 47 is a lever 51 extending upwardly through a cam slot 52 of a plate 53. This plate 53 is secured to one of the members of the frame 10, the slot 52 being provided with an inclined and diagonally arranged portion, and also with a pocket portion 54.

By this arrangement, it will be seen that as the lever 51 is given a limited rotary movement about the center of the shaft 47, the said lever will be moved outwardly and

the shaft 47 moved longitudinally until the lever 51 engages the pocket 54, which lever will then be held in said pocket by the action of the spring 48.

When the lever 51 is in the pocket 54, the members 42 will be moved out of engagement with the members 43.

By this arrangement, it will be seen that if the lever 51 is in the position shown in Figure 2, the clutch members 42 and 43 will be in engagement with each other. As the motor 33 is rotated, the belt 34 will drive the pulley 32. This in turn will drive the shaft 30 and the pinion 31 causing the gear 25 to be rotated, and the lugs 43 will cause the disc 37 to be rotated, and with it the crank 40, and the link 18 actuated, which will cause the agitator shaft 12 to be operated through the mechanism before described.

This provides means whereby the disc 37 may be positively driven through the gear 25 without noise or play, and also so arranged that the members 42 will easily and quickly disengage the members 43 with a minimum amount of power.

The members 42 and 43 are placed a considerable distance from the center of the shaft 19 to further eliminate the tendency toward looseness between the said members as the crank 18 passes its dead center.

By moving the lever 51 to the pocket 54, as before described, the agitator member may be thrown out of gear with the gear 25. The gear 25 being rigidly secured to the shaft 19 is also designed to impart motion to the wringer of the shaft 22.

I have, therefore, provided a clutch device of simple, durable and comparatively inexpensive construction which is particularly adapted to throw crank mechanism into and out of gear with a continuously rotating member.

I claim as my invention:

1. A shaft, a clutch member of disk formation, said clutch member having one of its faces provided with a series of tapering lugs projecting parallel with the axis of the shaft, a second clutch member of disk formation rotatively and slidably mounted on said shaft and parallel with the first said clutch member, said second clutch member being provided with a pair of semi-circular laterally extending flanges, the adjacent ends of said flanges each being provided with a lug, the lug of one of said flanges being spaced apart from the corresponding one of the opposite flange, the inner faces of said lugs being tapered to coat with the tapered faces of the lugs of the first said clutch member when the second clutch member is moved to its inward limit of movement, and means for moving said second clutch member toward and from said first clutch member.

2. A shaft, a clutch member of disk formation, said clutch member having one of its faces provided with a series of tapering lugs projecting parallel with the axis of the shaft, a second clutch member of disk formation rotatively and slidably mounted on said shaft and parallel with the first said clutch member, said second clutch member being provided with a pair of semi-circular laterally extending flanges, the adjacent ends of said flanges each being provided with a lug, the lug of one of said flanges being spaced apart from the corresponding one of the opposite flange, the inner faces of said lugs being tapered to coact with the tapered faces of the lugs of the first said clutch member when the second clutch member is moved to its inward limit of movement, a second shaft parallel with the first said shaft and capable of longitudinal movement, a yoke member rigidly secured to said second shaft, said yoke member being designed to encircle substantially one-half of the outer edge of the second disk, each end of said yoke member being provided with inwardly extending flanges to engage the opposite sides of said second clutch member, and yieldable means on said second shaft for yieldably holding the clutch members of said second disk in engagement with the clutch members of the first said disk.
3. A shaft, a clutch member of disk formation, said clutch member having one of its faces provided with a series of tapering lugs projecting parallel with the axis of the shaft, a second clutch member of disk formation rotatively and slidably mounted on said shaft and parallel with the first said clutch member, said second clutch member being provided with a pair of semi-circular laterally extending flanges, the adjacent ends of said flanges each being provided with a lug, the lug of one of said flanges being spaced apart from the corresponding one of the opposite flange, the inner faces of said lugs being tapered to coact with the tapered faces of the lugs of the first said clutch member when the second clutch member is moved to its inward limit of movement, a second shaft parallel with the first said shaft and capable of longitudinal movement, a yoke member rigidly secured to said second shaft, said yoke member being designed to encircle substantially one-half of the outer edge of the second disk, each end of said yoke member being provided with inwardly extending flanges to engage the opposite sides of said second clutch member, and yieldable means on said second shaft for yieldably holding the clutch members of said second disk in engagement with the clutch members of the first said disk, and a crank pin for the said second clutch member, substantially as described and for the purposes stated.

Des Moines, Iowa, September 20, 1921.

OLIVER B. WOODROW.
